WASHBASIN AND TOILET BOWL ASSEMBLY

Robert Snowball, Montreal, Quebec, Canada, assignor to The Robert Mitchell Co. Limited, Montreal, Quebec, Canada

Application March 7, 1947, Serial No. 732,977

4 Claims. (Cl. 4-3)

1

This invention relates to a compact wash basin and toilet bowl assembly for installation in places where space conservation is an important consideration such, for example, as in compartments, drawing rooms and other bedroom accommodations of railway passenger cars.

A salient feature of the invention consists in the provision of a compact wash basin and toilet bowl assembly in which the wash basin is mounted to swing about a vertical axis from a position directly above a fixed toilet bowl to an out-of-the-way position at one side of the toilet bowl. This assembly is particularly useful in restricted bedroom accommodations where the toilet bowl must be located relatively close to a bed or berth. In such cases the wash basin may be mounted a sufficient distance above the toilet bowl so that it will clear and overlie a portion of the bed or berth when swung to its out-of-the-way position with reference to the toilet bowl.

Another feature of the invention consists in arranging the wash basin, toilet bowl and associated parts, such as plumbing fittings, so that the space above the toilet bowl is left entirely clear when the wash basin is swung to its out-of-the-way position over the adjacent bed or berth.

A further feature of the invention consists in the manner in which the pipe connections to the drain opening and to the hot and cold water valves of the wash basin are arranged to swing to an out-of-the-way position with the wash basin.

A further feature of the invention consists in the provision of a sectional cabinet structure of novel design for enclosing the wash basin, toilet bowl, and the associated plumbing fittings so that these parts are covered in a sightly manner when the toilet bowl is not in use.

Other characteristic features and advantages of the invention will be set forth or made apparent in the following detailed description of the accompanying drawings, in which—

Fig. 1 is a front perspective view of my improved wash basin and toilet bowl assembly as it appears when the toilet bowl is not in use. This view shows the manner in which the cover of the upper section of the cabinet structure may be swung to one side to give access to the wash basin and to provide a supporting shelf for toilet accessories.

Fig. 2 is a front view of my improved wash basin and toilet bowl installation as it appears with the upper wash basin-containing section and an intermediate section of the cabinet structure swung to one side to provide a clear space

2

above the bottom section of the cabinet containing the toilet bowl. This view also shows the manner in which the upper wash basin-containing section of the cabinet structure clears and overlies an adjacent bed or bunk when swung to an out-of-the-way position at one side of the toilet bowl.

Fig. 3 is an enlarged view, partly in vertical section and partly in front elevation, of my improved wash basin and toilet bowl assembly.

Fig. 4 is an enlarged view, partly in side elevation and partly in vertical section, of my improved wash basin and toilet bowl assembly, the plane of the section being substantially along the line 4-4 of Fig. 3.

Fig. 5 is a plan view of the wash basin and bowl assembly as it appears when the upper wash basin-containing cabinet section and the intermediate cabinet section are swung to one side to give access to the toilet bowl contained in the lower cabinet section.

Fig. 6 is a fragmentary horizontal sectional view showing a slight modification in the design of the intermediate section of the cabinet structure.

Fig. 7 is an enlarged detail view illustrating the manner in which the upper wash basin-containing cabinet section and its cover are mounted for independent swinging movement about a common vertical axis.

As shown in these drawings, the cabinet structure of my improved wash basin and toilet bowl assembly comprises top, bottom, and intermediate cabinet sections respectively indicated at 5, 6 and 7, the top section 5 being equipped with a movable tray-forming cover 8.

The bottom cabinet section 6 is a stationary section enclosing a stationary toilet bowl 9 of standard design and dimensions. The top wall 10 of section 6 is provided with a suitable opening 10a (Fig. 5) and carries a hinged toilet seat 12.

Flushing water is supplied to bowl 9 through supply pipe 13 equipped with flushing valve 14. The mechanism provided for operating valve 14 may be of any suitable type and forms no part of the present invention. In the present instance I have shown a valve operating mechanism comprising an intermediately pivoted foot lever 15 having its front end extending forwardly into a corner recess 17 of cabinet section 6 and provided with a foot rest 15a. The rear end of lever 15 is connected by link 18 to a crank 19 provided at one end of a crank shaft 20 journaled in a suitable bearing 21. A second crank 22 at the opposite end of crank shaft 20 is operatively con-

55

nected to valve 14 by any suitable valve operating linkage such as that generally indicated at 23. Shaft 20 also carries and operates the toilet bowl dump pan 24.

The upper cabinet section 5 contains a wash basin 25. A drain fitting 27 (Figs. 3 and 4) containing any suitable type of drain valve 28, is secured in place beneath the bottom drain opening of basin 25. While the means for operating valve 28 constitutes no part of the present invention, I have shown merely by way of example a valve operating mechanism including a drain valve operating hand lever 29 which may be connected to drain valve 28 by flexible element 31, bell crank lever 32 and valve stem 33. When this type of drain valve operating mechanism is employed the flexible element 31 may be enclosed and guided by suitable tubing 34.

The outlet end 35 of drain fitting 27 is rigidly connected to the horizontally extending branch 36 of a swingably mounted drain elbow 37. The lower end of the vertical branch 38 of elbow 37 is swivelled to the upper end of a stationary bushing 39. As here shown, the swivel connection between drain elbow 37 and bushing 39 comprises a swivel flange 40 which is formed on the lower end of the vertical branch 38 of elbow 37 and is rotatably held against the upper end of bushing 39 by suitable coupling nut 41. The lower end of bushing 39 is connected by nipple 42 to the upper end of a drain trap 43. The lower end of drain trap 43 is connected by suitable drain piping 44 to the interior of bowl 9.

The bushing 39 extends through an opening provided in the lower horizontal extension 46 of a stationary bracket 47 and is secured in place by a suitable set screw 48.

Basin 25 is equipped with hot and cold water valves 50 and 51 operated by suitable handles 52 and 53. The water supplied to these valves is delivered to basin 25 through a suitable fitting 54 to which overflow pipe 55 is connected.

The inlet of cold water valve 51 is connected, by pipe 57, to the discharge end of a cold water passage 58 provided in a combined hot and cold water fitting 59. The inlet of hot water valve 50 is connected, by pipe 60, to the discharge end of a hot water passage 61 provided in fitting 59.

The upper end of the combined hot and cold water fitting 59 is swivelled in any suitable manner to the lower end of a stationary cold water fitting 62 provided with a cold water passage 63 through which cold water is passed from supply pipe 64 to the cold water passage 58 of fitting 59. The lower end of fitting 59 is similarly swivelled to the upper end of a stationary hot water fitting 65 provided with a hot water passage 66 through which hot water is passed from supply pipe 67 to the hot water passage 61 of fitting 59.

The cold water fitting 62 is fastened, by a bolt 68, to the lower surface of a horizontal extension 69 provided at the upper end of bracket 47. The hot water fitting 65 is fastened, by a screw 70, to an intermediate horizontal extension 71 of bracket 47.

The upper horizontal extension 69 of bracket 47 is formed with a vertically extending pivot 73 having a lower portion 73a of relatively large diameter and an upper portion 73b of smaller diameter. The lower portion 73a of pivot 73 is fitted in a corner opening 75 provided in the top portion 76 of the basin containing cabinet section 5. The upper portion 73b of pivot 73 is fitted in a bushing 77 provided in a corner opening 78 of the tray forming cover 8 of the cabinet

structure. The cover 8 may be secured against casual vertical displacement by a retaining pin 79 which is fitted in a hole 80 in the cover so that one end of the pin is received in a groove 81 provided in the upper portion 73b of pivot 73.

The bracket 47 is fastened to a suitable supporting wall 84 so that it provides a stationary support on which the cabinet section 5, the cover 8, the basin 25, the hot and cold water pipes 57 and 61 and the drain elbow 37 are mounted to swing about a common vertical axis. In this connection it may be noted that the hot and cold water fittings 59, 62 and 65 carried by the bracket 47 are arranged in axial alignment with each other and with the bushing 39 to which the lower end of the drain elbow 37 is swivelled. These hot and cold water fittings are therefore mounted to swing with the cabinet section 5 about a common vertical axis.

The front wall and a part of the right hand side wall of intermediate cabinet section 7 are mounted to swing with the upper cabinet section 5 from a position above to a position at one side of the lower cabinet section 6. In this connection it will be noted that the right hand side wall of cabinet section 7 comprises front and rear parts 87 and 88 fastened together by hinge connections 89 and that the forward part 87 of said side wall carries the front wall 90. The hinge 89 affords a vertical axis about which the front wall 90 and side wall portion 88 of cabinet section 7 are caused to swing with the upper cabinet section 5 through the agency of a slot and pin connection comprising a pin 92 extending upwardly from the front wall 90 of cabinet section 7 and working in a suitably curved slot 93 provided in the bottom of cabinet section 5. The pin and slot are arranged so that the swinging of cabinet section 5 to the dotted line position shown in Fig. 5 causes the front wall 90 and side wall portion 88 of cabinet section 7 to swing to the position shown in Fig. 5 so that the front wall 90 of cabinet section 7 is thereby disposed close to and parallel with the adjacent side of the berth or bunk 96 which is cleared by the cabinet section 5.

In Fig. 6 I have shown a slight modification of the intermediate cabinet section 7 which may be resorted to when the clearance between the toilet bowl 9 and the bunk or berth 96 is less than that shown in Fig. 5. According to the arrangement illustrated in Fig. 6 the swinging side wall section 87 of cabinet section 7 is divided into three relatively movable sections 87a, 87b and 87c connected to each other by spring hinges 98. The spring hinges 98 are arranged to cause the said side wall sections 87a, 87b and 87c to fold together as indicated by dotted lines when the collapsible side wall section 87 is swung about its hinge connection 89 to the stationary side wall section 88. This obviously reduces the clearance necessary between the bed or bunk 96 and the adjacent swinging side wall of cabinet section 7.

Having thus described the nature of my invention and a preferred embodiment thereof, it will be understood that various modifications may be resorted to within the scope and spirit of the invention as defined by the appended claims.

I claim:

1. A wash basin and toilet bowl assembly comprising a stationary toilet bowl, a wash basin mounted to swing about a vertical axis from a position directly above to a position at one side of the toilet bowl, a stationary cabinet section enclosing said toilet bowl, a movable cabinet section enclosing said wash basin and swingable

therewith about said axis, and an intermediate cabinet section interposed between the first mentioned cabinet sections, said intermediate cabinet section having its front wall mounted to swing with the upper cabinet section but about a different vertical axis.

2. A wash basin and toilet bowl assembly comprising a stationary toilet bowl, a wash basin mounted to swing about a vertical axis from a position directly above to a position at one side of the toilet bowl, a stationary cabinet section enclosing said toilet bowl, a movable cabinet section enclosing said wash basin and swingable therewith about said axis, and an intermediate cabinet section interposed between the first mentioned cabinet sections, said intermediate cabinet section having its front wall and a part of one side wall mounted to swing with the upper cabinet section but about a different vertical axis so that the distance travelled by the front wall of the intermediate section, in swinging from a position above to a position at one side of the toilet bowl, is substantially less than the distance travelled by the front wall of the upper cabinet section.

3. A wash basin and toilet bowl assembly as set forth in claim 2, in which the swingable side wall portion of the intermediate cabinet section is composed of a plurality of parts fastened together by vertical hinges so as to fold together during swinging movement of the front wall of the intermediate cabinet section to a position at one side of the toilet bowl.

4. A wash basin and toilet bowl assembly comprising a stationary toilet bowl, a bracket mounted above and to one side of said toilet bowl, an upper cabinet section supported by said bracket for swinging movement about a vertical axis from a position directly above to a position at one side of the toilet bowl, a wash basin enclosed by said cabinet section and swingable

therewith about said axis, a drain pipe including a stationary section and a swinging section connected between the stationary section and the wash basin and arranged to swing about said vertical axis, a hot and cold water fitting rotatably mounted on said bracket for turning movement about said vertical axis, hot and cold water valves carried by said wash basin, hot and cold water pipes connecting said valves to hot and cold water passages provided in said hot and cold water fitting, a bottom stationary cabinet section enclosing said toilet bowl and an intermediate cabinet section interposed between the toilet bowl enclosing cabinet section and the water basin enclosing cabinet section and having its front wall and a portion of its side wall arranged to swing with the wash basin enclosing cabinet section but about a different vertical axis so that the distance travelled by the front wall of the intermediate cabinet section, in swinging from a position above to a position at one side of the toilet bowl is substantially less than the distance travelled by the front wall of the upper cabinet section.

25
